(57) CLAIM

The ornamental design for a disc slot for optical disc drive, as shown and described.

DESCRIPTION

FIG. 1 is a front view of a disc slot for optical drive showing my new design;

FIG. 2 is an enlarged perspective view thereof;

FIG. 3 is an enlarged front view thereof;

FIG. 4 is a vertical sectional view thereof; taken along the line 4—4 of FIG. 1; and,

FIG. 5 is an enlarged vertical sectional view of FIG. 4.

The broken lines in FIGS. 1, 2, 4 and 5 are for illustrative purposes only and form no part of the claimed design.
